FRITZ LUBBERGER, OF CHICAGO, ILLINOIS, ASSIGNOR TO AUTOMATIC ELECTRIC COMPANY, OF CHICAGO, ILLINOIS, A CORPORATION OF ILLINOIS.

TELEPHONE-EXCHANGE TRUNKING SYSTEM.

1,304,076.

Specification of Letters Patent.

Patented May 20, 1919.

Application filed May 6, 1910, Serial No. 559,821. Renewed December 6, 1918. Serial No. 265,645.

To all whom it may concern:

Be it known that I, FRITZ LUBBERGER, a subject of the Emperor of Germany, and resident of Chicago, Cook county, Illinois, have invented a certain new and useful Improvement in Telephone-Exchange Trunking Systems, of which the following is a specification.

My invention relates to telephone systems of that kind in which main and branch exchanges are employed. Systems of this kind have been used in which automatic switches were provided for establishing connection between a subscriber's line of the branch exchange and a subscriber's line of the main exchange, or between lines located at different branch exchanges. It has also been possible in systems of this kind for the subscribers of the branch exchange to intercommunicate without using the apparatus at the main exchange. For such purpose so-called rotary connectors have been employed at the branch exchange, which connectors were made rotary on the tenth level and were thereby capable of selecting idle trunks leading to the main exchange, the other levels being used for making local calls. With this arrangement, however, the branch exchange would involve only ninety subscribers' lines, the entire tenth level of each connector being employed for automatic trunking to the main exchange, and no selectors being employed between the subscribers' lines and the said connectors.

The principal object of my invention is, therefore, to provide a system of this character in which ordinary or standard connectors can be employed at the branch exchange, and in which only one contact of each connector bank will be used for trunking purposes, whereby a small branch exchange may comprise ninety-nine subscribers' lines, all terminating in the banks of said connectors, and whereby the remaining terminal of each connector may be employed for automatically trunking to the main exchange when the connection is between a subscriber of the branch exchange and a subscriber of the main exchange, or between lines terminating at different branch exchanges, as will hereinafter more fully appear.

With my improved arrangement, therefore, the capacity of the branch exchange is not only materially increased, but the construc-

tion of the connectors is also simplified, it being possible to use ordinary or standard connectors in place of the so-called rotary connectors heretofore employed for this purpose.

To the foregoing and other useful ends my invention consists in matters hereinafter set forth and claimed.

In the accompanying drawings Figure 1 is a diagrammatic lay-out of an automatic telephone system embodying the principles of my invention.

Figs. 2, 3, 4 and 5 taken together show diagrammatically a complete circuit connection established between a calling branch exchange substation A and a main exchange substation A' in the system shown in Fig. 1.

The branch exchange shown at X' in Fig. 1 comprises the substations A to which there are allotted the line switches C. The connectors shown at E are accessible from the line switches C, and in turn have access to the substations in the branch exchange. The connectors E also control means by which the line switches C may obtain connection with the main exchange through a secondary line switch F, there being one of these switches for every connector. These switches F can be reached by the connectors over certain trunk lines assigned to them, but no others, as will be hereinafter more fully explained. Thus it will be seen that a substation A (Fig. 1) may call another substation in his own exchange through the medium of the line switch C and connector E, or he may extend the call to the substation A' in the main exchange through the line switch C, secondary switch F, repeater H, thence over trunk conductors to the main exchange, through a first selector I, second selector J, connector K to the substation A'. It will also be seen that it is possible for substation A' to call substation A through the medium of the line switches C', first selectors I, second selectors J, line switches C, connectors E, and thence to the substation A. Of course, the main exchange X may comprise a number of groups of substations A' together with their accompanying line, selector and connector switches.

The trunks leading from the secondary switches F at the branch exchange terminate in first selector switches I at the main exchange, just as do the trunk lines leading from the main exchange subscribers' line

switches C'. These trunk lines are used only for calls from the branch to the main exchange. For calling from the main exchange to the branch exchange a set of 5 trunks is provided leading from the banks of the second selectors J in the main exchange to line switches C in the branch exchange, which line switches are just like the branch exchange subscribers' line switches 10 and, like them, have access to the connectors E. Thus, after obtaining connection with one of these trunks, the main exchange subscriber may call any subscriber in the branch exchange, just as the subscriber at substation 15 A would call them.

In Fig. 2 there is shown diagrammatically a substation A, line switch C, master switch D and connector switch E.

Fig. 3 is a similar view of a secondary line 20 switch F controlled by the master switch D', which is similar to the master switch D (Fig. 2). Fig. 3 also shows a repeater H, which is used to repeat impulses delivered by the substations in the branch exchange to 25 the automatic switches in the main exchange.

Fig. 4 is a similar view of a first selector switch I and second selector J. At K (Fig. 5) there is shown a similar view of a connector. Fig. 5 also shows a substation A' and a line switch C' which are similar to the substation A and line switch C shown in Fig. 2. In the various drawings, a number of ringing current generators R and R' are 30 shown, while at M, M' and M² busy signaling machines are represented. As shown, each exchange is provided with a battery B having one terminal grounded, preferably its positive terminal.

40 Fig. 6 is a diagrammatic representation of the essential features of the master switch D (Fig. 2).

The automatic substations may be of any suitable or approved type. As herein represented, the substation A comprises the usual receiver 2, switch hook 3, transmitter 4, bells 5, condenser 6, impulse wheel 7, and impulse springs 8 and 9 which are made to break contact upon the backward rotation 50 of the impulse wheel 7. The switch hook 3 has a cam arm 17 attached to it which causes the springs 11 and 12 to be engaged as long as the receiver is on the hook, but as soon as the hook rises, the spring 12 is permitted to 55 engage the spring 13, thus bridging the receiver 2 and transmitter 4 in series across the line conductors 15 and 16 which lead to the line switch C.

The line switch C which is allotted to the 60 line of substation A is of the general type disclosed in British Patent No. 26,301 of 1906, being somewhat modified to operate in a two-wire system—that is, a system in which there is no ground connection used at 65 the substations to operate the central office

mechanism, or at least a part thereof. The switch C consists, essentially, of a magnet 18, the windings of which control the armatures 20 and 21 and plunger arm 19. To the end of the plunger arm 19 there is attached 70 a plunger 19^b (Fig. 6) which, when the arm is in an operated position, is forced into a bank of springs which form the terminals of trunk conductors leading to connectors E, and causes the springs 22, 23, 24 and 25 to 75 engage the springs 26, 27, 28 and 29, respectively. Although there is only one set of bank springs (22—29) shown, there may, however, be a plurality of such sets in each bank to which the plungers of the several 80 line switches C have access. The magnet 18 of the line switch C comprises four windings, namely, a pull-in winding 30, a cut-off winding 31, auxiliary winding 32 and line winding 33. The magnetic circuit of the 85 windings 30 and 31 is separate from that of the windings 32 and 33, due to the center of the core of the magnet being mounted upon the bracket 18^a. The winding 30, when energized, serves to pull up both armature 20 and the plunger arm 19, while the winding 31 will only pull up the armature 20 from an unoperated position, but will hold the plunger arm 19 in an operated position after it has once been pulled up by the 95 winding 30. The operation of the magnet 18 will be more fully explained later.

The master switch D is of the general type disclosed in the aforesaid British patent and also in the *American Telephone Journal* of June 6, 1908. It controls the plungers of the group of line switches of which the switch C is a member in such a manner that they are normally held in front of an idle trunk line leading to a connector 100 E. It consists essentially of the motor magnet 34 and the master switch bank *a* which comprises the individual segments *b* and the common segment 36. The wiper 37 serves to hold one of these individual segments in electrical connection with the common segment 36. The switch D also has a number of operating relays, one of which controls the locking plate 39. The ratchet wheel 38 is operated by the armature 40 of 105 the motor magnet 34.

The trunk conductors leading from the line switch banks to the connector pass through the springs of relay 41, the purpose of which will be more fully explained later. 110

The connector shown at E is of the general type disclosed in U. S. Letters Patent #815,176, granted March 13, 1906, to Keith, Erickson and Erickson. Among other details it comprises a shaft (not shown) carrying wipers 42, 43, and 44, which have a vertical movement controlled by the vertical magnet 45 and a rotary movement controlled by the rotary magnet 46. The slow relay 47 controls the private magnet 48, 115

which in turn controls the side switch which carries the wipers 49, 50, 51, 52 and 53. The relays 47 and 54 are slow acting—that is, they are slow to deenergize after their circuits are broken. The operation of the switch is controlled through the medium of the double-wound line relay 55. The release of the connector switch is brought about by means of the release magnet 57.

10 The first selector I shown in Fig. 4 is of the general type disclosed in U. S. Letters Patent #815,321, granted March 13, 1906, to Keith, Erickson and Erickson, being modified slightly to operate in conjunction with a two-wire system. It comprises the private magnet 144 which controls the side switch, carrying wipers 122, 123, 124 and 125, in the usual and well-known manner. It also comprises the slow-acting relays 132,

20 139 and 147, vertical magnet 140, rotary magnet 146, double-wound relay 121, release magnet 216 and a shaft carrying the wipers 141, 142 and 143. The mechanism of the selector is restored to normal position immediately upon the energization of its release magnet, rather than by its deenergization as shown in said selector patent.

The selector J is similar to the selector I.

As indicated in Fig. 1, the branch exchange is provided with a number of connectors E. The corresponding contacts in the banks of all these connectors are multipled together and connected with the respective subscribers' lines. In order to provide means for calling a subscriber in the main exchange, I find it advisable to leave some particular set of contacts in each connector bank disconnected from the corresponding contacts in the other banks.

40 In Fig. 2 is represented a portion of one level in the banks of two connector switches showing this disconnected contact. Each bank level, of course, consists of two sets of line contacts b and b' and a and a', respectively, and one set of private bank contacts b² and a², respectively. The first set of contacts of this level is shown as being reserved for the purpose of calling the main exchange. The line contacts of this set have 45 no connections at all. The first contact 92 of the private bank b² is connected with the relay 41 and with the line switch F (Fig. 3). Likewise, the first contact of the bank a² would be connected to a separate line switch 50 similar to the switch F, and to the relay 41 belonging to the trunk line leading to its own connector.

For convenience of explanation it is assumed that the contact which is reserved for 55 calling the main exchange is the first contact in the tenth or 0 level. Thus any subscriber at the branch exchange may obtain a trunk line leading to the main exchange by operating his calling mechanism for the digits 0 and 1. After obtaining connection with the

main exchange, the branch exchange subscriber may then obtain connection with any line which is connected with the said main exchange.

In order to give a clearer understanding 70 of my invention I will explain in detail the operations by means of which a subscriber at the substation A (Fig. 2) at the branch exchange may obtain connection with a substation in the main exchange and also with 75 another substation in the branch exchange. It will first be explained how connection is established with the main exchange substation 'A' (Fig. 5), the number of which is assumed to be 2220 in the main exchange. 80 As has been explained, the subscriber at substation A must prefix the digits 0 and 1 to the number 2220.

The first operation on the part of the calling subscriber is to remove the receiver 2 85 from the hook 3, which permits the hook to rise, thereby opening the circuit of the bells at springs 11 and 12, and bridging the receiver, transmitter and impulse springs in series across the line conductors 15 and 16 90 by permitting the engagement of springs 12 and 13. The closing of this bridge across the line conductors 15 and 16 closes an energizing circuit through the winding 33 of the magnet 18 of line switch C. This circuit extends from ground G' through springs 95 59 and 60, conductor 16, springs 12 and 13, impulse springs 8 and 9, receiver 2, transmitter 4, conductor 15, springs 61 and 62, winding 33 to battery lead 63, thence 100 through battery B to ground G. The line winding 33, upon energizing, attracts the armature 21, which forces spring 58 into engagement with spring 59. This closes a circuit extending from ground G' through 105 springs 59 and 58, winding 30 and winding 32 to battery lead 63, thence through battery B to ground G. The energizing of winding 30 pulls up the armature 20 and plunger arm 19. The pulling up of armature 20 110 breaks the circuit of line winding 33. The armature 21 does not fall back immediately, however, but is held up for a moment by the current flowing through the winding 32, which is short-circuited at the springs 19^a 115 and 20^a when the arm 19 operates, and therefore deenergizes slowly. Simultaneous with the attraction of the armature 20 is the attraction of the plunger arm 19. As before stated, the arm 19, in its operated 120 position, closes the lines to the connector E through the springs of the relay 41. As soon as the lines are closed to the connector E a circuit is closed extending from ground G² through lower winding of relay 55, springs 125 64 and 65 of relay 41, bank springs 29 and 25, conductor 16, springs 12 and 13 of substation A, impulse springs 8 and 9, receiver 2, transmitter 4, conductor 15, bank springs 22 and 26, springs 66 and 67 of relay 41,

130

upper winding of relay 55 to battery lead 63. The relay 55, upon energizing, closes an energizing circuit through the slow relay 54. This circuit extends from ground G³ through 5 springs 68 and 69 and relay 54 to battery. The relay 54, upon energizing, opens the release magnet circuit at springs 71 and 74. The closing of springs 73 and 74 puts the vertical magnet in readiness to receive im- 10 pulses by the grounding of spring 70. The engagement of springs 75 and 76 closes a circuit through the cut-off winding 31 of line switch C. This circuit extends from ground G⁴ through side switch wiper 49, 15 springs 75 and 76, bank springs 27 and 28 to the point 77, thence through winding 31 to battery. A branch also leads from the point 77 over normal conductor 78 to the private bank contact of the calling line in 20 the banks of all of the connectors that have access to the calling line, thus preventing another party from calling substation A while it is making a call. The circuit through the winding 31 is closed before the 25 armature 21 falls back, thereby keeping the plunger arm 19 and armature 20 in an attracted position. As soon as the bank springs 24 and 28 are brought into engagement by the plunger, a circuit is closed extending 30 from ground G⁵ through springs 24 and 28 to the contact 35 of the master switchbank, thence through wiper 37, common segment 36 and relay 79 to battery. The relay 79, upon energizing, closes the circuit of relay 35 35 80, which relay in turn closes a circuit through the motor magnet 34, lifts the pin 81 out of engagement with the locking plate 39 and puts a busy signal onto the lines of the idle line switches of the group controlled 40 by the master switch D. This busy signal reaches the line from the machine M by means of the induction between windings 32 and 33. The locking plate 39 is securely fastened to the shaft which controls the 45 plunger of line switch C, and the pin 81 engages an opening in the said locking plate only when the plungers stand directly in front of a trunk leading to one of the connectors E, and as long as the pin 81 is in en- 50 gagement with an opening in said locking plate, the shaft is held against rotation.

The circuit closed through the motor magnet by the energization of relay 80 extends from ground G⁶ through motor magnet 34, 55 interrupter springs 84^a, contact 82, armature 83 to battery. The motor magnet pulls up to break its own circuit at springs 84^a and to rotate the ratchet wheel 38 one step. By a suitable mechanical device the rotary 60 motion of the ratchet wheel is imparted to the plunger shaft, giving said plunger shaft an oscillatory motion to move the plungers in register therewith back and forth in front of the trunk terminals. As 65 the shaft is thus rotated, the hole in the

plate 39 is moved from under the pin 81, and the pin rests on top of the plate 39, which holds the armature 83 in engagement with contact 82. As the circuit of the motor magnet 34 is broken at the interrupter 70 springs, the armature 40 falls back and again closes the motor magnet circuit. Thus the magnet energizes and deenergizes in the manner of a buzzer to move the plungers to the next trunk, at which point the pin 75 81 will again engage an opening in the plate 39. If the next trunk should happen to be busy, the wiper 37 will find the contact next to the one last put in use grounded, and the relay 80 will be energized as before and 80 hence the plungers will be carried to the next idle trunk. As before stated, the busy signaling machine M supplies the busy signal to any subscriber that attempts to call while the master switch is operating. 85

The foregoing is the operation of the apparatus at the private branch exchange upon the removal of the receiver at substation A. The apparatus is now in readiness for the operation of the dial for the first digit by 90 the subscriber at substation A. As the dial is now operated in the usual manner for the first digit, which in this case is 0, the line at the substation is broken ten times by the separation of the impulse springs 8 and 9 95 by the impulse teeth 10. This opening of the line at substation A breaks the circuit of the double-wound line relay 55 of the connector E. The momentary deenergization of the relay 55 closes the circuit of the vertical magnets ten times to raise the shaft and shaft wipers ten steps to a point opposite the tenth level of contacts in the connector banks. The circuit through the vertical magnet extends from ground G³ through 100 springs 68 and 70, 74 and 73, (the relay 54, being slow acting, does not deenergize during the momentary interruptions of its circuit), vertical magnet 45, side switch wiper 50, relay 47 to battery. The relay 47 energizes in series with the vertical magnet upon the first impulse and, being slow acting, does not deenergize until after the last impulse has been delivered. In its energized position the relay 47 closes a circuit through 105 the private magnet 48. This circuit extends from ground G⁷ through springs 84 and 85, private magnet 48 to battery. The private magnet deenergizes upon the deenergization of the relay 47, and permits the side switch 110 to pass to second position. The side switch wiper 50 (in second position) connects the rotary magnet 46 to battery through the slow relay 47. The subscriber at substation A now operates the dial for the next digit 1. 115 The double line relay 55 again deenergizes once, this time closing a circuit through the rotary magnet 46 over a circuit extending from ground G³ through springs 68 and 70, 74 and 73, 86 and 87, rotary magnet 46, 120 125

- wiper 50, relay 47 to battery. The rotary magnet energizes once to rotate the shaft and shaft wipers one step onto the bank contacts of the trunk leading to the secondary switch F. The relay 47 energizes and deenergizes, as before, to close the circuit of the private magnet, which permits the side switch to pass to third position upon deenergizing.
- 5 The side switch wipers 52 and 53 (in third position) have no function at this time, as it will be remembered that the two line trunks have been disconnected from the contact upon which the connector now stands. In passing to the third position the wiper 49 shifts the holding ground for the cut-off winding 31 of the line switch C from ground G⁴ to ground G³. The passing of the wiper 50 to the third position closes an energizing circuit through the ringer relay 88, but this also is functionless at this time. The wiper 51 (in third position) closes a circuit through the relay 41 in multiple with the winding 89 of the secondary switch F. The circuit through the relay 41 extends from ground G⁸ through the wiper 51, springs 90 and 91, shaft wiper 43, private bank contact 92, conductor 93 and relay 41 to battery. The relay 41, upon energizing, disconnects the trunk conductors 94 and 95 from the connector E at the springs 64 and 65, and 66 and 67, and connects said conductors directly to the bank springs 109 and 110 of the switch F, over the conductors 102 and 103, by causing the engagement of the springs 66 and 96, and 65 and 97. The circuit through the winding 89 of the magnet 100 extends over the same circuit as traced for the relay 41 to the private contact 92, thence over the conductor 101, through the winding 89 to battery. The magnet 109, upon energizing, attracts the plunger arm 104, which acts in the same manner as the plunger arm 19 of the line switch C to force 45 the plunger into the bank of trunk terminals leading to a repeater H. The actuation of the plunger arm 104 also inserts the winding 105 in circuit in series with the winding 89 by shifting the spring 106 out of engagement with the spring 107 and into engagement with the spring 108. The engagement of the springs 109 and 110 with the springs 111 and 112, respectively, closes an energizing circuit through the double-wound line relay 113 of the repeater H. This circuit extends from ground G⁹ through the lower winding of said relay, springs 112 and 110, conductor 103, springs 97 and 65, 29 and 25, thence to and through substation A back over the line 15, springs 22 and 26, 66 and 96, conductor 102, springs 109 and 111 and the upper winding of the relay 113 to battery. The relay 113 energizes over this circuit and closes a circuit 55 through the slow relay 114 extending from ground G¹⁰ through the springs 115 and 116, relay 114 to battery. The relay 114, upon energizing, supplies a new holding ground for the windings 89 and 105. This ground extends from ground G¹¹ through the springs 117 and 118, bank springs 119 and 120, through the two windings of the magnet 100 in series, and thence to battery. A branch also extends to the conductor 101. The object of this ground on the conductor 75 101 is to supply a holding circuit for the relay 41, the release of the connector having made this necessary, as will now be explained. It will be remembered that upon the energization of the relay 41, the circuit 80 of the double line relay was broken, thus allowing it to deenergize and break the circuit of the relay 54. After a short time the relay 54 deenergizes and closes the circuit of the release magnet 57. This circuit extends from ground G³ through the springs 68 and 70, 74 and 71, release magnet 57 and springs 119^a and 120^a to battery. The release magnet energizes to release the switch immediately. As the shaft returns to normal position it disengages the springs 119^a and 120^a, thus breaking the circuit of the release magnet. Since the relay 54 is slow acting, this release of the connector does not take place until the line switch F and connector H have had time to operate to extend ground back over the conductor 101, as in the manner explained. The line switch C is held in an operated position over a circuit extending from the conductor 101 95 (which is grounded, as before described), through the springs 99 and 98, 27 and 23 and winding 31 of the line switch C to battery. As shown in the drawings, the springs of the relay 41 are make before break in 100 order that the talking circuit may be cut through to the repeater to energize the line relay 113 thereof before the line relay of the connector falls back. This is necessary in order that ground may be sent back from 105 the repeater to the conductor 101 before the ground is removed therefrom at the connector. Springs 98 and 99 of the relay 41 are adjusted to make before the rest of the springs to connect the holding circuit from 110 the repeater with that of the line switch before said circuit is broken at the connector.
- 50 The double-wound line relay 113, when energized, closes a circuit through the double-wound line relay 121 of the selector I. This circuit extends from ground G¹² through the lower winding of the relay 121, side switch wiper 122, conductor 126, impedance coil 127, springs 128 and 129, conductor 130, side switch wiper 123 and upper winding of the relay 121 to battery lead 131. The relay 121 operates to close the circuit of the slow relay 132. This circuit extends from ground G¹³ through the springs 133 125 130

and 134 and relay 132 to battery. The relay 132 energizes and opens the release magnet circuit at the springs 135 and 136.

The master switch D' operates the same 5 as the master switch D to move the plungers to the next idle trunk.

It is evident from the foregoing that, after the subscriber at substation A has called 01, a connection is completed through 10 the repeater H to a selector I in the main exchange. The connector E, which was used in establishing said connection, is restored to normal position. The switches are now in position to receive the impulses for 15 the third digit 2. As the circuit of the double-wound relay 113 of the repeater is broken twice in response to the subscriber's calling device, it deenergizes and breaks the circuit of the relay 121. The circuit of the 20 relay 114 of the repeater is also broken, but the relay 114, being slow-acting, does not deenergize during this momentary interruption of its energizing circuit. The relay 121 deenergizes twice in response to the 25 breaking of its circuit at the repeater, and closes the circuit of the vertical magnet 140 twice. This circuit extends from ground G¹³ through the springs 133 and 137, 135 and 138, relay 139, magnet 140 and side switch wiper 124 to the battery lead 131. The vertical magnet energizes twice to raise 30 the shaft and shaft wipers 141, 142 and 143 two steps to a point opposite the second level of bank contacts. The relay 139 in the 35 circuit with the vertical magnet is slow-acting, and therefore acts in the same manner as the relay 47 of the connector E to hold closed a circuit through the private magnet 144 until the last impulse has been 40 delivered to the vertical magnet. The private magnet then deenergizes and permits the side switch to pass to second position. The side switch wiper 124 (in second position) closes a circuit extending from ground 45 G¹² through interrupter springs 145, rotary magnet 146, slow relay 147 and side switch wiper 124 to battery. The rotary magnet 146 energizes over this circuit to rotate the shaft and shaft wipers one step onto the 50 bank contact of a trunk leading to a second selector switch J, push down private magnet armature, and to break its own circuit at springs 145. If the first contact upon which the shaft wipers are rotated is idle, 55 the rotary armature falls back, because its circuit is broken at springs 145, and releases the private magnet armature, which in turn allows the side switch to pass to the third position. Should the first trunk 60 be busy, however, the private wiper 142 will find a guarding ground potential upon the first contact, in a manner hereinafter more fully explained. A circuit is now completed extending from the ground potential

on the private bank contact through the 65 private wiper 142, side switch wiper 125 (in second position), private magnet 144 to battery, thereby holding the private magnet in an energized position, which locks the side switch in second position. The rotary 70 magnet again energizes immediately upon its deenergization and rotates the shaft wipers another step, as before. If this second trunk is busy, the operation will be repeated to rotate the shaft wipers to the first 75 idle trunk leading to a selector J, whereupon the private magnet deenergizes and permits the side switch to pass to third position. The wipers 122 and 123, upon passing to third position, close a circuit through 80 the double-wound line relay 148. This circuit extends from ground G¹⁴ through lower winding of relay 148, side switch wiper 149, shaft wiper 143, side switch wiper 122, thence over the heavy conductor to and through 85 impedance coil 127 of repeater H, springs 128 and 129, conductor 130, wipers 123, 141 and 150, upper winding of relay 148 to battery. The relay 148 energizes and closes the circuit of the slow relay 154 in the same 90 manner as the circuit of relay 132 of selector I was closed. The relay 154 energizes, and in addition to performing the functions that were performed by relay 132, it extends a guarding ground potential back 95 over conductor 155 to the private bank contact of the selector J in the banks of all of the first selectors that have access to the selector J. This ground extends from ground G¹⁵ through side switch wiper 152, 100 springs 156 and 157 and conductor 155 to the said private bank contacts. The relay 147 of the selector I being slow acting remains energized for a moment after the side switch has passed to third position. Thus it 105 supplies ground to the private bank contact above referred to between the time that the side switch passes to third position and the time that the ground potential is put back by relay 154 of the second selector. The 110 relay 147 supplies this guarding potential over a circuit extending from ground G¹⁶ through springs 158 and 159 to private wiper 142. This guarding ground is to prevent another switch from stopping on 115 the trunk leading to selector J before relay 154 of selector J operates. The relay 147 is quicker than the relay 132, however, and deenergizes in time to close a holding circuit for relay 132 before it has time to deenergize after its circuit is broken by the deenergization of relay 121. The holding circuit of relay 132 extends from ground G¹⁵ to wiper 142, as before traced, thence through side switch wiper 125 and springs 126 and 159 to and through relay 132 to 120 battery lead 131.

The selector J operates in the same man-

ner as the selector I for the fourth digit 2 to extend the trunk lines to the connector K. The connector K operates in the same manner for the last two digits 2 and 0 as did the connector E of Fig. 1 for the digits 0 and 1. Briefly, the operation is as follows: The double-wound relay 160 energizes as soon as the side switch wipers of selector J pass to third position. The relay 160, upon energizing, closes a circuit through the slow relay 161, which in turn energizes and puts a holding ground back to the release relays of selectors I and J to hold them in an energized position. Upon the operation of the dial for the fifth digit 2, the repeater operates as before described to break the circuit of relay 160. The relay 160 thereupon deenergizes twice and closes the circuit of the vertical magnet 163, which operates to raise the shaft and wipers 164, 165 and 166 two steps. The private magnet relay 167 energizes and closes the circuit of the private magnet 168. A moment after the line is open for the last time, the private magnet is allowed to deenergize, which permits the side switch to pass to second position. The subscriber now operates the dial for the last digit 0. The impulses, instead of being sent to the vertical magnet, are transferred to the rotary magnet, which energizes to rotate the shaft and shaft wipers ten steps onto the line of the called subscriber. If this line is idle, the side switch is permitted to pass to the third position in the usual manner. Thus far the operation has been similar to the operation of the connector E, before described. When the wipers 169 and 170 pass to the third position, the conductors 174 and 175 are completed to the line of the called subscriber through the condensers 176 and 177.

In passing to third position the wiper 171 puts a guarding ground onto the private bank contact of the called line in the banks of all of the connectors that have access to the called line. This circuit extends from ground G¹⁸ through the wiper 171, springs 219 and 220 of the busy locking relay 221, private wiper 165 to the said private bank contacts. A circuit also extends from this ground at the private wiper 165 over the conductor 222 through the winding 223 of the line switch C' and thence to battery. The armature 224 is attracted upon the closure of this circuit and operates to bring the spring 190 into engagement with the spring 189, which closes the line to the called substation. The operation of the armature 224 also disconnects the line winding 225 from the called line. This prevents the called party from calling while a connector is standing on his line. The wiper 173 (in third position) completes a circuit through the ringer relay 178. This circuit

extends from ground G¹⁷ through the interrupter 179, springs 180 and 181, relay 178, side switch wiper 173 and relay 167 to battery. The ringer relay, upon energizing, shifts the springs 182 and 183 out of engagement with the springs 184 and 185 and into engagement with the springs 186 and 187, respectively, thereby opening the line between the calling and called substations and bridging the ringing current generator R' onto the line of the called substation. A ringing current now passes through the bells 188 over a circuit extending from one side of the generator R' through the springs 187 and 183, wiper 170, shaft wiper 164, springs 189 and 190, conductor 191, bells and condenser 188, springs 192 and 193, conductor 194, wipers 166 and 169, ringer relay springs 182 and 186 to the opposite side of the generator R'. The subscriber at substation A', upon hearing the signal, removes the receiver from the hook. This operation allows the spring 193 to disengage the spring 192 and to engage spring 195. When this occurs, or as soon thereafter as the ringer relay 178 is deenergized by the interrupter 179, a circuit is closed through the double-wound backbridge relay 196 of the connector K. This circuit extends from ground G¹⁸ through wiper 171, lower winding of relay 196, springs 182 and 184, wipers 169 and 166, conductor 194, springs 193 and 195, impulse springs 197, receiver 198, transmitter 199, conductor 191, springs 190 and 189, wipers 164 and 170, springs 183 and 185, upper winding of relay 196 to battery. Talking current for the called substation is also furnished over the circuit just traced. The relay 196, upon energizing, breaks the circuit of the ringer relay 178. The springs 200 and 201 also engage, but without results at this time. A conversation may now be carried on between the two subscribers at substations A and A' without interruption.

The release of the apparatus used in establishing this connection is initiated by the calling subscriber in replacing the receiver on the hook. It will be remembered that the relay 113 of the repeater is energized during the conversation over a circuit extending through the springs 12 and 13 of substation A. Therefore, when the receiver at substation A is placed on the hook the springs 12 and 13 disengage and break the circuit of relay 113. When the relay 113 deenergizes it breaks the circuit of the relays 114 and 160 (Fig. 5). The relay 114, upon deenergizing, breaks the circuit of the windings 89 and 105 of the switch F, and also breaks the holding circuit of the relay 41 and winding 31. The breaking of these holding circuits permits the two trunking switches F and C and the relay 41 to restore to normal

position. As the relay 160 deenergizes it breaks the holding circuit of the relays 161, 154 and 132 of the switches K, J and I, respectively. The relay 161, upon energizing, 5 operates to close a circuit through the release magnet 202. The circuit through the magnet 202 extends from ground G¹⁹ through the springs 203 and 204, springs 205 and 206, magnet 202, spring 208 and contact 207, 10 thence to battery. The opening of the circuit of the relays 154 and 132 allows them to deenergize and close the circuits of their respective release magnets. The circuit through the release magnet 209 of the selector J extends from ground G²⁰ through the springs 210 and 211, springs 212 and 213, magnet 209, contact 214 and spring 215 to battery. The circuit through the release magnet 216 of the selector I extends from 15 ground G¹³ through the springs 133 and 137, springs 135 and 136, magnet 216, contact 217 and spring 218 to battery. The various release magnets, upon energizing, release their respective switches. The shafts of the 20 switches, upon returning to normal position, break the circuits of the release magnets. All of the switches used in the connection are thus restored to normal position and are in readiness for another call.

25 30 Returning now to that point in the operation of setting up the connection when the connector K passes onto the called line, but before the side switch has passed to the third position: If the called line is busy the private wiper 165 will find a guarding ground on the private bank contact, as has been described. When the relay 167 deenergizes after the last impulse of the last digit has been delivered, the guarding ground at the 35 40 private bank contact provides a locking circuit for the private magnet 168. This circuit extends through the wiper 165, springs 220 and 219, lower winding of the relay 196, springs 184 and 182, side switch wiper 169 (in second position), springs 227 and 226 of the relay 167 and private magnet 168 to battery. The side switch thus remains locked in second position and the relay 196 energizes, closing a circuit extending from 45 50 ground G²¹ through the springs 228 and 229, 230 and 231, relay 221 and springs 200 and 201 to battery. The relay 221 energizes to disconnect the rotary magnet from the spring 204 at the springs 232 and 233. It 55 60 also shifts the holding ground for the relay 196 and magnet 168 from the private wiper to ground G²² by shifting the spring 219 out of engagement with the spring 220 and into engagement with the spring 234. This prevents the connector side switch from passing to the third position in case the called line becomes idle.

The engagement of the springs 235 and 236 upon the energizing of the relay 221 puts

a busy signal on the line of the calling subscriber. This circuit extends from battery through the secondary of the induction coil 237, springs 236 and 235, wiper 170, ringer springs 183 and 185, condenser 177, thence over the heavy conductor to and through 65 the substation A, back over the heavy conductor, through the lower winding of the relay 160 of the connector K to ground. The calling subscriber, upon receiving the busy signal, replaces the receiver on the hook, 70 thereby releasing the switches in a manner hereinabove described.

If, now, the subscriber A desires to call another subscriber in his own exchange, the line switch C is operated, upon the removal 80 of the receiver from the hook, in the same manner as before to complete connection to the connector E. The subscriber at substation A will now call the desired number, which will consist of two digits. The connector E now operates in exactly the same manner as did the connector K, before described, to complete connection to the called line.

The calling subscriber receives his talking 90 battery current from the circuit through the double-wound line relay 55 instead of through the double-wound relay of the repeater, as in the other connection. The release of the switches in this connection is 95 brought about in the same manner as before described. When connection is made with one of the branch exchange substations through the medium of the connector E, the relay 41 is not operated and the talking circuit between the two substations extends from the calling substation over the conductors shown in heavy lines in Fig. 1 to the springs 66 and 65 of the relay 41, thence through the spring 67 on one side of the line 100 105 and the spring 64 on the other side, condensers 238 and 239, normally closed springs of the ringer relay 88, side switch wipers 53 and 52 and shaft wipers 42 and 44 to the bank contacts of the called line. 110

From the foregoing it will be seen that I provide an improved trunking system in which ordinary or standard connectors are employed for making local calls, and also for extending a trunking connection to another exchange. Heretofore, as previously explained, rotary connectors have been used for this purpose. Connectors of this kind are not only more or less complicated, as they are required to be automatically rotary in one or more levels thereof, but they also tend to limit the capacity of the branch exchange, because only ninety subscribers' lines can be connected with the bank of each connector. In other words, at least one entire level of a rotary connector must be given over to automatic trunking, thus allowing ninety contacts for subscribers' lines. 115 120 125

With my improved arrangement each connector will accommodate ninety-nine subscribers' lines, and with a sufficient number of connectors the trunking to the main exchange will be entirely satisfactory. For local calls the connectors of my improved system operate in the usual manner. When the call is from the branch exchange to the main exchange, or from one branch exchange to another branch exchange, then the connectors of my improved system operate in a different way, and serve merely to connect the calling line with the trunk leading to a non-numerical trunking switch. This trunking switch then selects an idle repeater, and through the medium of the repeater the calling subscriber controls the two sides of the telephone line in series to successively operate the first and second selectors and the connector at the main exchange, if the call is to a line terminating at the latter. If the call is from one branch exchange to another, then the repeater is used for controlling the selectors at the main exchange, and for then controlling a connector at the branch exchange. When the connector at the branch exchange is employed for establishing a connection with the main exchange, it does not remain in operation, as it is released upon the establishment of such connection. It is, however, at such time not available for use by other subscribers, as the trunk to which it is allotted is made busy and remains so until after the subscribers are through using it for conversing. In other words, the non-numerical trunking switch that selects the idle repeater is substituted for the connector in the establishment of the connection with the main exchange.

40 What I claim as my invention is:—

1. In a telephone system, a branch exchange provided with automatic connectors, subscribers' lines terminating in the banks of said connectors, a main exchange, and means including a particular contact of each connector bank for effecting a trunking connection from the branch exchange to the main exchange, which particular contacts are excluded from the trunking connections between the two exchanges.

2. In a telephone system, a branch exchange, a main exchange, connectors at the branch exchange, subscribers' lines terminating in the banks of said connectors, means at the branch exchange for automatically selecting idle connectors, means for effecting a trunking connection from the branch exchange to the main exchange by a particular operation of any one of said connectors, and means for automatically releasing the connector without breaking the established trunking connection between the two exchanges.

3. In a telephone system, a branch ex-

change, a main exchange, connectors at the 65 branch exchange, subscribers' lines terminating in the banks of said connectors, means at the branch exchange for automatically selecting idle connectors, non-numerical trunking switches at the branch exchange for use 70 in trunking therefrom to the main exchange, means whereby a particular operation of any connector serves to operate one of said non-numerical trunking switches, and means for automatically releasing the operated connector without disturbing the connection established by the non-numerical trunking switch.

4. In a telephone system, a trunk line, a relay for establishing connection therewith, 80 a connector, telephone lines terminating in the bank of said connector, means whereby a particular operation of said connector serves to energize said relay, and means whereby the energizing of said relay restores 85 the connector to normal position.

5. In a telephone system, a trunk line, a relay controlling connection therewith, a connector, telephone lines terminating in the bank of said connector, an energizing circuit 90 for said relay controlled at a certain point in the connector bank, whereby a particular operation of said connector serves to establish a connection with said trunk line and to release said connector, and a talking circuit 95 including said trunk, the circuit of said relay being excluded from the talking circuit.

6. In a telephone system, an automatic connector, means for using said connector in effecting a calling connection, means for automatically restoring said connector to normal position after operation thereof, without disturbing the calling connection, means for releasing the calling connection, and means preventing further use of said connector until after said connection is released. 105

7. In a telephone system, a branch exchange provided with automatic connectors, subscribers' lines terminating in the banks of said connectors, a main exchange, means including a particular contact of each connector bank for effecting a trunking connection from the branch exchange to the main exchange, which particular contacts are excluded from the trunking connections between the two exchanges, and means for controlling said connectors over two sides of the calling line in series. 110

8. In a telephone system, a branch exchange, a main exchange, connectors at the 120 branch exchange, subscribers' lines terminating in the banks of said connectors, means at the branch exchange for automatically selecting idle connectors, means for effecting a trunking connection from the branch exchange to the main exchange by a particular operation of any one of said connectors, and means for automatically releasing the con- 125

5 nector without breaking the established trunking connection between the two exchanges, and means for controlling said connectors over two sides of the calling line in series.

9. In a telephone system, a branch exchange, a main exchange, connectors at the branch exchange, subscribers' lines terminating in the banks of said connectors, means at 10 the branch exchange for automatically selecting idle connectors, non-numerical trunking switches at the branch exchange for use in trunking therefrom to the main exchange, means whereby a particular operation of any 15 connector serves to operate one of said non-numerical trunking switches, means for automatically releasing the operated connector without disturbing the connection established by the non-numerical trunking switch, 20 and means for controlling said connectors over two sides of the calling line in series.

10. In a telephone system, a trunk line, a relay for establishing connection therewith, a connector, telephone lines terminating in 25 the bank of said connector, means whereby a particular operation of said connector serves to energize said relay, means whereby the energizing of said relay restores the connector to normal position, and means for 30 controlling said connector over two sides of the calling line in series.

11. In a telephone system, a trunk line, a relay controlling connection therewith, a connector, telephone lines terminating in the 35 bank of said connector, an energizing circuit for said relay controlled at a certain point in the connector bank, whereby a particular operation of said connector serves to establish a connection with said trunk, a talking 40 circuit including said trunk, the circuit of said relay being excluded from the talking circuit, and means for controlling said connector over two sides of the calling line in series.

45 12. In a telephone system, an automatic connector, means for using said connector in effecting a calling connection, means for automatically restoring said connector to normal position after operation thereof without disturbing the calling connection, means for releasing the calling connection, means preventing further use of said connector until after said connection is released, and means for controlling said connector over 50 two sides of the calling line in series.

13. In a telephone system, a branch exchange provided with automatic connectors, each connector being provided with a bank 60 consisting of groups of contacts, subscribers' lines terminating in all but one of said contacts, a main exchange, and means including the remaining contact of each connector bank for effecting a trunking connection from the branch exchange to the 65 main exchange, said connectors having first

one motion to select a group and then another motion to find a called line in the predetermined group, both of said motions being controllable over the two sides of the calling line in series, an automatic progressively movable switch at the main exchange, 70 and means for operating said switch over said trunking connection.

14. In a telephone system, a branch exchange provided with automatic connectors, 75 subscribers' lines terminating in the banks of said connectors, a main exchange, and means including a particular contact of each connector bank for effecting a trunking connection from the branch exchange to the 80 main exchange, which particular contacts are excluded from the trunking connections between the two exchanges, said connectors having first one motion to select a group and then another motion to find a called line in 85 the predetermined group, both of said motions being controllable over the two sides of the calling line in series.

15. In a telephone system, a branch exchange, a main exchange, connectors at the 90 branch exchange, subscribers' lines terminating in the banks of said connectors, means at the branch exchange for automatically selecting idle connectors, means for effecting a trunking connection from the 95 branch exchange to the main exchange by a particular operation of any one of said connectors, and means for automatically releasing the connector without breaking the established trunking connection between the 100 two exchanges, said connectors having first one motion to select a group and then another motion to find a called line in the predetermined group, both of said motions being controllable over the two sides of the 105 calling line in series.

16. In a telephone system, a branch exchange, a main exchange, connectors at the branch exchange, subscribers' lines terminating in the banks of said connectors, 110 means at the branch exchange for automatically selecting idle connectors, non-numerical trunking switches at the branch exchange for use in trunking therefrom to the main exchange, means whereby a particular operation of any connector 115 serves to operate one of said non-numerical trunking switches, and means for automatically releasing the operated connector without disturbing the connection established by the non-numerical trunking switch, said connectors having first one motion to select a group and then another motion to find a called line in the predetermined group, both of said motions being 120 controllable over the two sides of the calling line in series.

17. In a telephone system, a trunk line, a relay for establishing connection therewith, a connector, telephone lines terminat- 130

- ing in the bank of said connector, means whereby a particular operation of said connector serves to energize said relay, and means whereby the energizing of said relay restores the connector to normal position, said connector having first one motion to select a group and then another motion to find a called line in the predetermined group, both of said motions being controllable over the two sides of the calling line in series. 5
18. In a telephone system, a trunk line, a relay controlling connection therewith, a connector, telephone lines terminating in the bank of said connector, an energizing circuit for said relay controlled at a certain point in the connector bank, whereby a particular operation of said connector serves to establish a connection with said trunk, and a talking circuit including said trunk, the circuit of said relay being excluded from the talking circuit, said connector having first one motion to select a group and then another motion to find a called line in the predetermined group, both of said motions being controllable over the two sides of the calling line in series. 10
19. In a telephone system, an automatic connector, means for using said connector in effecting a calling connection, means for automatically restoring said connector to normal position after operation thereof without disturbing the calling connection, means for releasing the calling connection, and means preventing further use of said connector until after said connection is released, said connector having first one motion to select a group and then another motion to find a called line in the predetermined group, both of said motions being controllable over the two sides of the calling line in series. 15
20. In a telephone system, a branch exchange provided with automatic connectors, each connector being provided with a bank consisting of groups of contacts, subscribers' lines terminating in all but one of said contacts, a main exchange, means including the remaining contact of each connector bank for effecting a trunking connection from the branch exchange to the main exchange, a central source of talking and operating current, and means whereby the current for operating purposes is controlled over the two sides of the calling line in series, an automatic progressively movable switch at the main exchange, and means for operating said switch over said trunking connection. 20
21. In a telephone system, a branch exchange provided with automatic connectors, subscribers' lines terminating in the banks of said connectors, a main exchange, means including a particular contact of each connector bank for effecting a trunking connec- 25
- tion from the branch exchange to the main exchange, which particular contacts are excluded from the trunking connections between the two exchanges, a central source of talking and operating current, and means whereby the current for operating purposes is controlled over the two sides of the calling line in series. 70
22. In a telephone system, a branch exchange, a main exchange, connectors at the branch exchange, subscribers' lines terminating in the banks of said connectors, means at the branch exchange for automatically selecting idle connectors, means for effecting a trunking connection from the branch exchange to the main exchange by a particular operation of any one of said connectors, means for automatically releasing the connector without breaking the established trunking connection between the two exchanges, a central source of talking and operating current, and means whereby the current for operating purposes is controlled over the two sides of the calling line in series. 75
23. In a telephone system, a branch exchange, a main exchange, connectors at the branch exchange, subscribers' lines terminating in the banks of said connectors, means at the branch exchange for automatically selecting idle connectors, non-numerical trunking switches at the branch exchange for use in trunking therefrom to the main exchange, means whereby a particular operation of any connector serves to operate one of said non-numerical trunking switches, means for automatically releasing the operated connector without disturbing the connection established by the non-numerical trunking switch, a central source of talking and operating current, and means whereby the current for operating purposes is controlled over the two sides of the calling line in series. 80
24. In a telephone system, a trunk line, a relay for establishing connection therewith, a connector, telephone lines terminating in the bank of said connector, means whereby a particular operation of said connector serves to energize said relay, means whereby the energizing of said relay restores the connector to normal position, a central source of talking and operating current, and means whereby the current for operating purposes is controlled over the two sides of the calling line in series. 85
25. In a telephone system, a trunk line, a relay controlling connection therewith, a connector, telephone lines terminating in the bank of said connector, an energizing circuit for said relay controlled at a certain point in the connector bank, whereby a particular operation of said connector serves to establish a connection with said trunk, a talking circuit including said trunk, a talking circuit including said trunk, 90
- 105
- 110
- 115
- 120
- 125
- 130

- the circuit of said relay being excluded from the talking circuit, a central source of talking and operating current, and means whereby the current for operating purposes is controlled over the two sides of the calling line in series.
26. In a telephone system, an automatic connector, means for using said connector in effecting a calling connection, means for automatically restoring said connector to normal position after operation thereof without disturbing the calling connection, means for releasing the calling connection, means preventing further use of said connector until after said connection is released, a central source of talking and operating current, and means whereby the current for operating purposes is controlled over the two sides of the calling line in series.
27. In a telephone system, a branch exchange provided with automatic connectors, each connector being provided with a bank consisting of ten parallel rows of contacts of ten contacts each, subscribers' lines terminating in ninety-nine of said contacts, a main exchange, means including the remaining contact of each connector bank for effecting a trunking connection from the branch exchange to the main exchange, numerical switches at said main exchange, and repeaters controllable over any subscriber's line to control said numerical switches.
28. In a telephone system, a branch exchange provided with automatic connectors, subscribers' lines terminating in the banks of said connectors, a main exchange, means including a particular contact of each connector bank for effecting a trunking connection from the branch exchange to the main exchange, which particular contacts are excluded from the trunking connections between the two exchanges, numerical switches at said main exchange, and repeaters controllable over any subscriber's line to control said numerical switches.
29. In a telephone system, a branch exchange, a main exchange, connectors at the branch exchange, subscribers' lines terminating in the banks of said connectors, means at the branch exchange for automatically selecting idle connectors, means for effecting a trunking connection from the branch exchange to the main exchange by a particular operation of any one of said connectors, means for automatically releasing the connector without breaking the established trunking connection between the two exchanges, numerical switches at said main exchange, and repeaters controllable over any subscriber's line to control said numerical switches.
30. In a telephone system, a branch exchange, a main exchange, connectors at the branch exchange, subscribers' lines terminating in the banks of said connectors,

means at the branch exchange for automatically selecting idle connectors, non-numerical trunking switches at the branch exchange for use in trunking therefrom to the main exchange, means whereby a particular operation of any connector serves to operate one of said non-numerical trunking switches, means for automatically releasing the operated connector without disturbing the connection established by the non-numerical trunking switch, numerical switches at said main exchange, and repeaters controllable over any subscriber's line to control said numerical switches.

31. In a telephone system, a trunk line, a relay for establishing connection therewith, a connector, telephone lines terminating in the bank of said connector, means whereby a particular operation of said connector serves to energize said relay, numerical switches at the other end of said trunk line, and repeaters controllable over any subscriber's line to control said numerical switches.

32. In a telephone system, a trunk line, a relay for establishing connection therewith, a connector, telephone lines terminating in the bank of said connector, means whereby a particular operation of said connector serves to energize said relay, means whereby the energizing of said relay restores the connector to normal position, numerical switches at the other end of said trunk line, and repeaters controllable over any subscriber's line to control said numerical switches.

33. In a telephone system, a trunk line, a relay controlling connection therewith, a connector, telephone lines terminating in the bank of said connector, an energizing circuit for said relay controlled at a certain point in the connector bank, whereby a particular operation of said connector serves to establish a connection with said trunk, a talking circuit including said trunk, the circuit of said relay being excluded from the talking circuit, numerical switches at the other end of said trunk line, and repeaters controllable over any subscriber's line to control said numerical switches.

34. In a telephone system, an automatic connector, means for using said connector in effecting a calling connection, means for automatically restoring said connector to normal position after operation thereof without disturbing the calling connection, means for releasing the calling connection, means preventing further use of said connector until after said connection is released, numerical switches, and repeaters controllable over any subscriber's line to control said numerical switches for use in establishing said calling connection.

35. In a telephone system, a trunk line, an automatic switch having a plurality of bank

5 contacts and a movable wiper, a relay connected in circuit with one of said contacts and adapted to be energized when said wiper connects with said contact to extend a connection to said trunk line and to release the said automatic switch without destroying the connection.

10 36. In a telephone system, a trunk line, an automatic switch having a plurality of bank contacts and a movable wiper, a relay connected in circuit with one of said contacts and adapted to be energized when said wiper connects with said contact, means controlled by said relay for extending a connection to 15 said trunk line, and means whereby the energizing of said relay restores said automatic switch to normal position.

20 37. In a telephone system, a trunk line, an automatic switch having a plurality of line contacts and a bank of private contacts, a private wiper, a relay connected in circuit with one of said private contacts and adapted to be energized when said private wiper connects with said private contact, and means 25 controlled by said relay for extending a connection to said trunk line and for releasing said automatic switch without destroying the connection to said trunk line.

30 38. In a telephone system, a trunk line, an automatic switch having a plurality of line contacts and a bank of private contacts, a private wiper, a relay connected in circuit with one of said private contacts and adapted to be energized when said private wiper connects with said private contact, means 35 controlled by said relay for extending a connection to said trunk line, and means whereby the energizing of said relay restores said automatic switch to normal position.

40 39. In a telephone system, a trunk line, an automatic switch having a plurality of bank contacts and a movable wiper, a relay connected in circuit with one of said contacts and adapted to be energized when said wiper connects with said contact, means controlled by said relay for extending a connection to said trunk line and for eliminating the said automatic switch from the established connection, and means for controlling said automatic switch over two sides of a line circuit in series.

45 40. In a telephone system, a trunk line, an automatic switch having a plurality of bank contacts and a movable wiper, a relay connected in circuit with one of said contacts and adapted to be energized when said wiper connects with said contact, means controlled by said relay for extending a connection to said trunk line, means whereby the energizing of said relay restores said automatic switch to normal position, and means for controlling said automatic switch over two sides of a line circuit in series.

50 41. In a telephone system, a trunk line, an automatic switch having a plurality of line

contacts and a bank of private contacts, a private wiper, a relay connected in circuit with one of said private contacts and adapted to be energized when said private wiper connects with said private contact, means 70 controlled by said relay for extending a connection to said trunk line and for releasing the said switch without interfering with the trunk line connection, and means for controlling said automatic switch over two sides 75 of a line circuit in series.

42. In a telephone system, a trunk line, an automatic switch having a plurality of line contacts and a bank of private contacts, a private wiper, a relay connected in circuit 80 with one of said private contacts and adapted to be energized when said private wiper connects with said private contact, means controlled by said relay for extending a connection to said trunk line, means whereby the 85 energizing of said relay restores said automatic switch to normal position, and means for controlling said automatic switch over two sides of a line circuit in series.

43. In a telephone system, calling lines, a progressively movable connector switch, means for connecting any one of said lines with said switch, a plurality of other lines having terminals in said connector switch, means whereby said connector may be operated to establish a connection from the calling line to any one of said other lines, a relay, means for applying a potential to a terminal of one of said other lines for energizing said relay to extend a connection 100 from a calling line to said other line and to disconnect said switch from the extended connection, and means for supplying current for talking purposes to some of said lines from a central source. 105

44. In a telephone system, calling lines, a progressively movable connector switch, means for connecting any one of said lines with said switch, a plurality of other lines having terminals in said connector switch, 110 means whereby said connector may be operated to establish a connection from the calling line to any one of said other lines, a relay, means for applying a potential to a terminal of one of said other lines for 115 energizing said relay to extend a connection from a calling line to said other line and to release the said connector switch, an automatic switch on said other line, and means for then transmitting impulses from the 120 calling line over said other other line to operate said automatic switch.

45. In a telephone system, calling lines, a progressively movable connector switch, means for connecting any one of said lines 125 with said switch, a plurality of other lines having terminals in said connector switch, means whereby said connector may be operated to establish a connection from the calling line to any one of said other lines, 130

- a relay, means for applying a potential to a terminal of one of said other lines for energizing said relay to extend a connection from a calling line to said other line and to 5 eliminate the connector switch from the connection without interfering with the said connection, and means for controlling said connector switch over two sides of the calling line in series.
- 10 46. In a telephone system, calling lines, a progressively movable connector switch, means for connecting any one of said lines with said switch, a plurality of other lines having terminals in said connector switch, 15 means whereby said connector may be operated to establish a connection from the calling line to any one of said other lines, a relay, a means for applying a potential to a terminal of one of said other lines for energizing said relay to extend a connection from a calling line to said other line and for releasing the connector switch from the extended connection, said connector switch having two motions, one to select a group 20 of said other lines, and another to locate an individual line in the selected group.
47. In a telephone system, a trunk line, a relay controlling connection therewith, a talking circuit including said trunk line, a 30 connector, telephone lines terminating in the bank of said connector, an energizing circuit for said relay controlled at a certain point in the connector bank, whereby a particular operation of said connector serves to 35 establish a connection with said trunk line and to eliminate the connector from the talking circuit, the circuit of said relay being excluded from the talking circuit.
48. In a telephone system, a trunk line, 40 a relay controlling connection therewith, a talking circuit including said trunk line, a connector, telephone lines terminating in the bank of said connector, an energizing circuit for said relay controlled at a certain 45 point in the connector bank, whereby a particular operation of said connector serves to establish a connection with said trunk line and to eliminate the connector from the talking circuit, the circuit of said relay being excluded from the talking circuit, and means for supplying current for talking 50 purposes to said lines from a central source.
49. In a telephone system, a trunk line, an automatic switch having a plurality of 55 bank contacts and a movable wiper, a relay and means controlled thereby, said relay connected in circuit with one of said contacts and adapted to be energized when said wiper connects with said contact to extend 60 a connection through the medium of said means to said trunk line and to release the said automatic switch without destroying the connection, and means for supplying current for talking purposes to said lines 65 from a central source.
50. In a telephone system, a trunk line, an automatic switch having a plurality of bank contacts, a movable wiper, a relay connected in circuit with one of said contacts and adapted to be energized when said wiper 70 connects with said contact, and means controlled by said relay for extending a connection to said trunk line and for eliminating the said automatic switch from the connection.
- 75 51. In a telephone system, a trunk line, an automatic switch having a plurality of line contacts and a bank of private contacts, a private wiper, a relay connected in circuit with one of said private contacts and adapted to be energized when said private wiper connects with said private contact, and means controlled by said relay for extending a connection to said trunk line and for eliminating the said automatic switch from the ex- 80 tended connection.
52. In a telephone system, calling lines, a progressively movable connector switch, means for connecting any one of said lines with said switch, a plurality of other lines having terminals in said connector switch, 85 means whereby said switch may be operated to establish a talking circuit from a calling line to any one of said other lines, a relay, means for applying a potential to a terminal of one of said other lines for energizing said relay to extend a connection from a calling line to said other line and to release the said connector switch, an automatic switch on said other line, and means for transmitting 90 impulses from the calling line over two sides of the talking circuit in series to operate said automatic switch.
- 95 53. In a telephone system, calling lines, a progressively movable connector switch, 105 means for connecting any one of said lines with said switch, a plurality of other lines having terminals in said connector switch, means whereby said switch may be operated to establish a talking circuit from a calling 110 line to any one of said other lines, a relay, means for applying a potential to a terminal of one of said other lines for energizing said relay to extend a connection from a calling line to said other line and to release the said connector switch, an automatic switch on said other line, and means for transmitting 115 impulses over two sides of the talking circuit in series to operate said switches.
- 120 54. In a telephone system, subscribers' lines, means for performing a series of successive selecting operations to establish a connection between two of said lines, a trunk terminal, a trunk normally connected thereto, a second trunk normally disconnected therefrom, means for first performing certain of said selecting operations over said terminal and the normally connected trunk, means for disconnecting said normally con- 125 130

5 nected trunk and connecting said normally disconnected trunk when said selecting operations have reached a certain point, and means for then completing said selecting operations over said last-mentioned trunk.

55. In a telephone system, subscribers' lines divided into groups, means for establishing a connection between two of said lines, said means including a trunk having a 10 single terminal adapted to be seized by a calling subscriber and a pair of branches extending from said trunk, one branch normally connected thereto and extending toward certain of said subscribers' lines and 15 the other branch extending toward other of said lines, and means for first extending the call over said normally connected branch and completing the connection over said other branch if it is desired to establish a 20 connection with a subscriber reached by said last-mentioned branch, and means for disconnecting said normally connected branch during talking.

56. In a telephone system, a trunk line 25 having a single terminal at one end thereof and a pair of branches, one normally connected with said terminal and the other normally disconnected therefrom, a switching relay for controlling said connections, a contact maker, step-by-step means for controlling the operation of said contact maker, and bank contacts with which said contact maker is adapted to engage, certain of said contacts being operatively connected with 30 said switching relay, whereby when said contact maker is operated to engage with said connected contacts said switching relay is energized to shift the connection of said trunk terminal to the normally disconnected 35 branch.

57. In a telephone system, trunk lines having a single terminal at one end thereof and a pair of branches, one normally connected with said terminal and the other normally disconnected therefrom, a switching mechanism in said trunk, line and pilot wipers controlled by said mechanism, bank contacts with which said wipers are adapted to engage, a relay operatively connected 40 with certain of the contacts in the bank engaged by said pilot wiper, means for energizing said relay when said pilot wiper comes in contact with said contacts, and means operated by the energization of said 45 relay for shifting the connection of said trunk terminal to the normally disconnected branch of the trunk.

58. In a telephone system, a trunk line 50 having a single terminal at one end thereof and a pair of branches, one normally connected with said terminal and the other normally disconnected therefrom, a switching mechanism in the normally connected branch, said switching mechanism comprising a pair of line wipers and a pilot wiper,

means for moving said wipers in a vertical plane and then rotating the same, bank contacts with which said wipers engage, certain of the contacts in one level of the bank engaged by said pilot wiper being operatively 70 connected with a relay, means for closing a circuit through said relay when said pilot wiper is stepped up to a proper level and then rotated the proper degree in order to engage said contacts, and means controlled 75 by the energization of said relay to shift the connection of said trunk terminal to the normally disconnected branch.

59. In a telephone system, a calling line, a plurality of trunk lines accessible to said 80 calling line, each of said trunk lines having a first branch and a second branch, a switching device for shifting a connection from the first branch to the second branch, a trunking switch for said second branch having 85 individual terminals in said switching device, a group of lines for said first branch, a group of lines for said second branch, means whereby said calling line in establishing a connection first extends said connection over 90 said first branch, means for then operating said switching device to shift said connection to said trunking switch over said individual terminals and said second branch, a called line, and means including said trunking switch for completing the connection to said called line over a line of one of said groups of lines.

60. In a telephone system, a relay, an automatic switch provided with rotary wipers 100 and means for closing a circuit to energize said relay, and a talking connection independent of said wipers closed by the energization of said relay.

61. In a telephone system, a relay, an automatic switch provided with rotary wipers and means for closing a circuit to energize said relay, and a talking connection independent of said wipers closed by the energization of said relay, said talking connection 110 including a trunk individual to said relay.

62. In a telephone system, a trunk, a switch at one exchange, a switch at another exchange, branch connections from said 115 trunk to said switches, means for controlling said switches over said trunk, one of said branches being normally open, and a relay controlled over one branch to close said open branch.

63. In a telephone system, a trunk having a main portion and a plurality of branch portions, means for making local calls over the main portion and one branch portion, and means for making long distance calls 125 over the main portion and another branch portion, one branch being sufficient for local calls, and both branches being necessary for establishing a long distance call.

64. In a telephone system, a trunk, a 130

switch at one exchange, a switch at another exchange, branch connections from said trunk to said switches, and means for controlling said switches over said trunk, one branch being sufficient for local calls, and both branches being necessary for establishing a long distance call.

65. In a telephone system, a relay, an automatic switch provided with rotary wipers and automatic means for closing a circuit to energize said relay, and a talking connection independent of said wipers closed by the energization of said relay.

66. In a telephone system, a relay, an automatic switch provided with rotary wipers and circuit means for closing a circuit to energize said relay, and a talking connection independent of said wipers closed by the energization of said relay, said talking connection including a trunk individual to said relay.

67. In a telephone system, a trunk having a main portion and a plurality of branch portions, circuit controlling means for making local calls over the main portion and one branch portion, automatic means for making long distance calls over the main portion and another branch portion, one of said branches being normally open, and a relay controlled over one branch to close said open branch.

68. In a telephone system, a trunk, a

switch at one exchange, a switch at another exchange, branch connections from said trunk to said switches, circuit means for controlling said switches over said trunk, one of said branches being normally open, and a relay controlled over one branch to close said open branch.

69. In a telephone system, a trunk having a main portion and a plurality of branch portions, automatic means for making local calls over the main portion and one branch portion, and automatic means for making long distance calls over the main portion and another branch portion, one branch being sufficient for local calls, and both branches being necessary for establishing a long distance call.

70. In a telephone system, a trunk, a switch at one exchange, a switch at another exchange, branch connections from said trunk to said switches, and impulse sending means for controlling said switches over said trunk, one branch being sufficient for local calls, and both branches being necessary for establishing a long distance call.

Signed by me at Chicago, Cook county, Illinois, this 27 day of April, 1910.

FRITZ LUBBERGER.
